UNITED STATES PATENT OFFICE.

THEODORE F. ODELL, OF NYACK, NEW YORK.

BOTTLE-CLOSURE.

SPECIFICATION forming part of Letters Patent No. 782,757, dated February 14, 1905.

Application filed May 7, 1904. Serial No. 206,928.

To all whom it may concern:

Be it known that I, THEODORE F. ODELL, a citizen of the United States, residing at Nyack, in the county of Rockland and State of New York, have invented new and useful Improvements in Bottle-Closures, of which the following is a specification.

This invention relates to closures of that class having means for preventing the practical filling of a bottle after the original contents thereof have been dispensed, to overcome and obstruct irregular practices with relation to certain distinct liquids in the market, and obstruct deception of the public, and thereby protect both the manufacturer and the purchaser.

The invention consists in the construction and arrangement of parts, which will be more fully hereinafter set forth.

In the drawings, Figure 1 is a transverse vertical section through a bottle-neck and a portion of the body, showing a closure therein and embodying the features of the invention, the closure being shown in elevation. Fig. 2 is a view similar to Fig. 1, showing the closure also in transverse vertical section. Fig. 3 is a horizontal section of the lower part of the closure on the line 3 3, Fig. 2. Fig. 4 is a detail plan view of a resilient securing-ring used in connection with the closure.

Similar numerals of reference are employed to indicate corresponding parts in the several views.

The numeral 1 designates the body of a bottle or analogous device having a neck 2, the bore through the neck being formed at an intermediate point, with a circumferential concavity 3 to provide a chamber to establish communication between different parts of the closure. The lower part of the neck is contracted by an inwardly-extending enlargement 4, and between said enlargement and a circumferential rib 5 just below the chamber 3 the neck is reduced in thickness to facilitate the insertion of the closure by removing the frictional obstruction from the lower extremity of the latter as much as possible. Above the chamber 3 and near the outlet of the neck a circumferential groove 6 is formed for a

locking device, which will be hereinafter set forth.

The closure consists of a tubular body comprising upper and lower sections 7 and 8, connected by an intermediate flush-joint 9, the upper section adjacent to said joint having a solid partition 10 formed therein. The section 8, adjacent to the joint 9, is formed with a series of openings 11, and above the partition 9 and close to the latter the section 7 also has a series of openings 12, extending there-around, both sets of openings 11 and 12 communicating with the chamber 3. The lower extremity of the section 8 is thickened to form a valve-chamber 13, and at the lower terminal of the valve-chamber is an inwardly-projecting annular flange 14, providing a valve-seat with which a ball or spherical valve 15 co-operates. Above the upper terminal of the valve-chamber 13 and between said terminal and the partition 10 a spherical float 16, of suitable material, has free movement and operates in conjunction with the valve 15. The float 16 prevents the valve 15 from passing entirely out of the valve-chamber 13, and to reduce the friction on the valve 15 and float 16 the chamber 13 has inwardly-projecting ribs 17 at diametrically opposite points, and the part of the section 8 above said chamber also has similar ribs 18, which terminate at their upper ends just below the openings 11. It will be seen that these ribs 17 and 18 respectively reduce the surface with which the valve 15 and float 16 contact, and thereby the valve and float are rendered more sensitive in their operation. In the upper part of the exterior of the section 7 a circumferential groove 19 is formed, and when the closure is inserted a resilient ring 20 is disposed in said groove 19 and pressed downwardly with the closure into the neck of the bottle, the said ring springing out and engaging the groove 6 when the closure has been fully inserted, to form a locking means to prevent withdrawal of the closure. It will be understood that the groove 19 will be deep enough to hold the resilient locking-ring 20 and permit it to be compressed sufficiently to avoid obstructing the introduction of the closure in the bottle-neck.

Before the closure is inserted in the bottle-neck the body 1 is filled with the liquid desired to be introduced and protected against spurious imitation by the closure set forth. 5 The closure is then inserted and the lower end thereof contacts with the enlargement 15. The sealing of the bottle is finally completed by inserting in the upper end of the section 7 a cork stopper 21, which is withdrawn when 10 it is desired to dispense the contents of the bottle. In dispensing the contents of the bottle the latter is canted to cause the float 16 to move toward the openings 11 and the valve 15 to clear its seat, the fluid then passing 15 through the section 8, the opening 11, into the chamber 3, and from the latter, through the openings 12, out through the section 7. During the dispensing operation the float 16 moves backward and forward in its confined 20 space and obstructs the displacement of the valve 15 from its chamber. When the bottle is disposed in erect position, the valve 15 returns to its seat and the float resumes the position shown by Fig. 2. It will be seen that 25 it will be impossible for any one to insert a wire or any implement into the lower part of the closure or to displace the float and valve and hold the latter parts in open position. Hence the improved closure will be exception- 30 ally effective in obstructing the introduction of imitation or spurious liquids in the bottle as a substitute for that originally introduced therein.

It is proposed to construct the several parts 35 of the closure of a non-corrosive material, so

that they may be used in connection with bottles in which acids or corroding liquids are placed. After the closure is locked in place in the bottle-neck it will be impossible to remove the same except by breaking the neck, 40 and this condition of the neck would at once indicate that the bottle had been tampered with, and thus be of advantage to the purchaser. It will also be understood that changes in the proportions, dimensions, and minor 45 details may be resorted to without departing from the spirit of the invention.

Having thus fully described the invention, what is claimed as new is—

A bottle-neck having an intermediate concavity forming a chamber, a closure inserted in the said neck and consisting of tubular sections connected by an intermediate joint, the lower end of the upper section having a solid partition and both sections having openings 55 therethrough above and below the partition in communication with the said chamber, the lower section also having a valve-chamber and lower seat and ribs projecting inwardly thereinto, ribs projecting inwardly into the lower 60 section above the valve-chamber, a spherical valve coöperating with said seat, and a float in the lower section above the valve.

In testimony whereof I affix my signature in presence of two witnesses.

THEODORE F. ODELL.
